UNITED STATES PATENT OFFICE.

GEORGES ESTOPPEY, OF ORANGE, NEW JERSEY, ASSIGNOR TO MUSA, ESTOPPEY & CO. INC., OF NEW YORK, N. Y., A CORPORATION OF NEW YORK.

SIGHTING APPARATUS.

1,296,642.

Specification of Letters Patent. Patented Mar. 11, 1919.

Application filed July 24, 1918, Serial No. 246,484.

To all whom it may concern:

Be it known that I, GEORGES ESTOPPEY, a citizen of Switzerland, residing at Orange, in the county of Essex and State of New Jersey, have invented Sighting Apparatus, of which the following is a specification.

My invention relates to sighting apparatus and more particularly to apparatus for determining by observation the point in the travel of an aeroplane or like moving body at which an object, such as a bomb, must be released in order to strike a target, such as a building of the enemy, the device of this application being an improvement upon that described in my co-pending application Serial No. 207330, filed Dec. 15, 1917.

It is well known in accordance with the laws of motion that when an object, such as a bomb, is released from a moving body, such as an aeroplane, it assumes an initial speed in the direction of movement of the aeroplane or other moving body equal to the speed of the latter; so that if an aeroplane is moving horizontally at a given speed there will be a tendency for the released bomb to continue to move horizontally at the same speed. The aviator in order to hit the target is accordingly obliged to release the bomb before the aeroplane is above the target. The point at which the bomb or other object should be released depends upon a number of factors including the altitude of the moving body, the speed thereof relatively to the ground, and the resistance of the air to the released bomb or other object. It is the aim of the present invention to provide apparatus which, taking the above factors into account, will determine the proper point in the travel of the moving body at which the bomb or other such object should be released so that it will fall upon the target.

Another object of the invention is to provide a device of the character referred to which is convenient to operate and of an improved construction.

Another object is to provide a device for the purpose stated which has as an operative part thereof timing mechanism arranged to be readily controlled and observed by the operator of the sighting apparatus. Other objects of my invention will appear more fully hereinafter.

A clear understanding of the invention can best be had by reference to the accompanying drawings showing sighting appa-

ratus embodying the invention in the form now considered best and illustrating the operation of said apparatus. In said drawings:

Figure 1 is a view partly in elevation and partly in section taken on the line 1-1 of Fig. 3, the axis of the sighting member being shown in various positions occupied thereby in the operation of the apparatus.

Fig. 2 is a fragmentary side elevation of 65 the same, partly broken away.

Fig. 3 is a vertical cross-section taken on the line 3-3 of Fig. 1, but showing the sighting member and its supporting bracket in elevation, the upper portion of the sight- 70 ing member being broken away.

Fig. 4 is a horizontal sectional view taken on line 4-4 of Fig. 1.

Fig. 5 is a fragmentary sectional view taken on line 5-5 of Fig. 6 and showing 75 the arrangement of the timing mechanism with respect to the sighting member.

Fig. 6 is a view of the sighting member and timing mechanism viewing Fig. 5 from the left.

Fig. 7 is a diagram explaining the operation of the apparatus.

Referring to the drawings, Figs. 3 and 4, the numeral 1 represents a top side plate of the body of an aeroplane. Carried by the 85 plate 1 is a casing 2, which contains a portion of the operating mechanism of the apparatus. The sighting member 3, as shown, is carried by a bracket 4, which is pivoted to the casing 2 for movement about a horizontal axis by means of the pivot 5. The said pivot, as shown, is mounted in the upper portion of the casing 2 intermediate the ends thereof, the bracket 4 being carried by the outer portion of the pivot so that the 90 said bracket and the sighting member 3 are located outside of but close to the body of the aeroplane in a convenient position for use of the sighting member. For positioning the sighting member, the bracket 4 has a

slidable connection with a member 7 which is movable horizontally in a manner to be hereinafter more fully described, the bracket 4 having desirably a slot 8 extending longitudinally of the sighting member through which extends the shank of a screw 9 threaded into the member 7. The member 7, as shown, is in the form of a lateral projection from a slide 10 which is movable longitudinally upon a cylindrical guide 11, the latter 105

110

being provided at its outer end with an enlargement 12 forming a stop to limit the movement of the slide 10 in one direction. Suitable means are provided for securing the slide 10 to the guide 11, such means as shown comprising a screw 14 threaded into a boss 15 upon the slide 10 and arranged to press at its inner end upon a bearing block 16 resting against the guide 11. A spring 17, which is shown as a helical spring surrounding the inner reduced end of the screw 14 and bearing upon the block 16 and a shoulder upon the said screw, is desirably employed to yieldingly hold the block 16 in position against the guide 11 when the screw 14 is released. The guide 11 surrounds and is supported by a horizontal rod 18, the ends of which, as shown, are mounted in bearings in the casing 2, said rod being held against longitudinal movement by any suitable means, such as a collar 19 and the bevel gear 20 which are secured to the opposite ends of the said rod and bear against the respective end walls of the casing 2. The rod 18 is provided adjacent its opposite ends with screw threads 21 and 22, respectively, one of which is right handed and the other left handed, the guide 11 being threaded upon the screw threads 21. Threaded adjacent its outer ends upon the screw threads 22 is a sleeve 24, the inner end of which is arranged to surround the adjacent end of the guide 11. The sleeve 24 is designed to act as a stop to limit the movement of the slide 10 to the right, referring to Fig. 1, and to this end is provided with a bearing surface 25 against which the right hand end of the slide 10 is adapted to engage. To hold the slide 10, guide 11 and sleeve 24 against rotation about the axis of the rod 18, I provide means such as a longitudinal guide-rod 26 mounted in fixed bearings in the casing 2 and slidably engaged by upwardly extending portions of said slide, guide and sleeve. The rod or shaft 18 is rotated by any suitable means, such as crank 27 and the train of gears 28, 29 and 30 driven by the crank. This train of gears, as shown, is a speed increasing train so that for one rotation of the crank 27 50 a number of rotations of the screw rod 18 are effected.

In the operation of the device it is necessary for the operator to know when an interval of time equal to that required for the falling object to fall from the body in motion to the ground has elapsed. In accordance with this invention a suitable timing mechanism is so arranged that the operator may be advised of the elapse of this interval 60 of time without discontinuing to sight along the sighting member 3. The latter, as shown, is in the form of an ordinary sighting tube with usual cross-hairs at right angles to each other and intersecting in the optical axis or line of vision and with an eye

piece 30 of rubber or any other suitable material. Intermediate the ends of the sighting tube there is a diaphragm 31 which cuts out a portion of the field of the sighting tube. The timing mechanism shown comprises a stop watch 32, the operating mechanism of which may be of usual construction. This stop watch is firmly held in position in a casing 33 which is mounted for axial rotation in a frame 34, the casing 33 being held against axial displacement from the frame 34 by means of an annular rim 35 on the casing which projects into a recess in the front end of the frame 34, and by means of a ring 36 which is secured to the rear of the casing 33 and bears against the rear of the frame 34. The frame 34 is secured to the tube 3 by means of suitable end flanges, one of which is shown as 37. The frame 34 is provided with a suitable slot through which the operating stem 38 on the stop watch 32 passes, this slot permitting the said watch to be rotated axially within the frame. The stop watch, as shown, sets down a short distance within the sighting tube; although the major portion thereof extends above the said tube, as more fully shown in Figs. 5 and 6. The pointer or hand of the watch is of greater length than the radius of the frame 34 so that it projects beyond the said frame and 90 can be seen at its lower end in sighting through the sighting tube, when the said pointer or hand is in its lower position. The dial of the stop watch is desirably graduated so as to indicate in place of time intervals 100 heights from the ground corresponding to intervals of time during which an object will fall from the height in question to the ground. For example, in Fig. 6, the numeral 3 on the watch dial corresponds to 3000 ft.; the numeral 4 to 4000 ft. and so on, and the time required for the index or hand 38' to travel a distance from 0 to 3 is the time required for an object to fall from a height of 3000 ft. to the ground. In constructing the scale, allowance may be made for the vertical resistance of the air upon the falling bomb so that when the pointer 38' travels a distance equal to that from 0 to 3 the object will fall from a height of 3000 ft. to the 110 ground even though its downward movement is resisted by the air. Surrounding the forward edged portion of the frame 34 is an annular frame 40 to which is secured a mounting 41 for a glass 42 arranged in front of the stop watch. The frame 40 is connected to a frame member 43 which is secured to the sighting tube.

Suitable means are desirably provided whereby the same member by which the rotation of the rod 18 is controlled also controls the starting of the stop watch. To this end the crank 27 is provided with a hub 44 which contains a portion 45 projecting outwardly away from the axis of rotation of the crank. 130

The cam member 44 co-acts with a roller 46 supported in a bearing upon one end of a wire 47 which extends through a rigid tubular covering 48, the wire 47 being provided at its opposite end with a member 49 which is arranged coaxially with the stop watch 32 and with a member 50 movable longitudinally in a guide in the frame 43 when the parts are in position preparatory to making an observation 5 for setting the sighting tube. The upper end of the tube 48 may be secured as by a suitable bracket 51 to a stationary part of the machine. The construction and arrangement of parts is such that the parts 49 and 50 are arranged adjacent each other when the sighting tube is in proper position preparatory to making the observation referred to, but the member 50 is located downwardly away from the member 49 in all other positions of 10 the sighting tube. Means such as the spring 52 may be employed to yieldingly hold the wire 47 in position with the roller 46 bearing against the cam member 44. The inner end of the member 50 bears against the lower end of a lever 53 pivoted intermediate its 15 ends at 54 and bearing at its upper end upon a bell crank lever 55 pivoted at 56 and having a forked outer end engaging a recess in the stem 38, so that when the member 50 is forced inwardly the stem 38 will be forced 20 downwardly to start the stop watch.

It is desirable to provide means for taking into account the horizontal resistance of the wind upon the forwardly moving 25 bomb and with this end in view I have secured to the slide 10 a needle or pointer 60 which travels horizontally across a scale 61 carried by a bracket 62 mounted within the casing 2. The upper end of the pointer 60 30 as shown in Fig. 3, desirably travels in a guide 63. The scale or chart 61 is designed so as to provide for the desired change in setting the apparatus because of the resistance of the wind to the falling object. 35 This scale also indicates, as will be explained later, the absolute speed of the aeroplane with respect to the ground. The scale is desirably made translucent and an ordinary incandescent light 65 is provided within 40 the casing 2 to illuminate the scale by night. A transparent window 66 is provided on the outside of the casing 2 to permit ready inspection of the scale or chart 61 and the pointer 60.

In operation, with the slide 10 bearing 45 against the stop surface 12 of the guide 11, and secured in this position upon the said guide, the crank 27 is first rotated to bring the forward end of the guide 11 into engagement with the collar 19. The operator also determines the height of his 50 machine from a barometer or other suitable means and rotates the stop watch 32 until the fixed reference mark 80 upon the glass 55 42 registers with the graduation on the face

of the stop watch corresponding to such height. During this adjustment the pointer or hand 38' of the stop watch is moved from its former vertical position of rest, shown in Fig. 6, in an anti-clockwise direction. At this setting of the apparatus, the line of vision of the sighting member makes its maximum angle p (see Fig. 1) with the vertical and the stop 24, 25 is so positioned that if the slide 10 were moved into engagement with the said stop the line of vision through the sighting member would be vertical. The aviator then approaches the target most desirably in the direction of the wind either with or against the same. 60 In approaching the target, the aeroplane is maintained at a substantially constant height above the ground and is operated at a constant speed. In approaching the target the operator sights through the member 3, with the latter inclined its maximum distance away from the vertical as stated, until the target appears in the line of vision through the sighting member. At this moment the operator begins the rotation of 65 the crank 27 to move the sighting member 3 about its axis, so as to maintain the target in the line of vision of the sighting member. As soon as the operator begins to rotate the crank 27 the projection 45 on the member 44 moves the wire 47 so as to cause member 49 to shift the member 50 inwardly and through the levers 53 and 55 to force in the stem 38 of the stop watch to start the 70 movement of the hand or pointer 38' from its adjusted position of rest in a clockwise direction. The rotation of the crank 27 is continued by the operator so as to maintain the target in the line of vision along the 75 sighting member until the pointer 38' reaches 80 a vertical position registering with the vertical cross-hair of the sighting tube. At this moment the crank has been rotated for 85 a period of time corresponding to the time required for the bomb to drop to the ground 90 from a height equal to that at which the aeroplane is traveling and the rotation of the crank is immediately stopped. At this 95 time the axis or line of vision of the sighting member 3 makes an angle "r" with the vertical (see Fig. 1). In order to make 100 correction for the resistance of the wind to the forward movement of the bomb as it falls from a height equal to that at which the aeroplane is traveling and the rotation of the crank is immediately stopped. At this 105 time the axis or line of vision of the sighting member 3 makes an angle "r" with the vertical (see Fig. 1). In order to make 110 correction for the resistance of the wind to the forward movement of the bomb as it falls to the ground, assuming the aeroplane to be traveling directly against the wind, the 115 operator observes the point on the chart 61 at which the needle 60 intersects the horizontal line representing the height at which the aeroplane is traveling. He then rotates the crank 27 so as to shift the slide 10 and 120 guide 11 forwardly again a distance equal to the distance on the chart 61 between the nearest upwardly extending heavy line and the lighter line to the left at the horizontal 125 line representing the height at which the 130

aeroplane is traveling. This operation can be easily and quickly effected by observing the position of the needle 60 with respect to the chart 61 at the height in question. During this complete movement of the sighting tube and of the slide 10 and guide 11, the surface 25 of the member 24 has been moved forwardly a distance equal to the distance slide 10 and guide 11 have been moved rearwardly, the threads 21 and 22 being of equal pitch. The axis or line of vision of the sighting member at this time makes an angle r' (see Fig. 1) with the vertical. The operator then loosens screw 14 and moves the slide 10 backwardly until it engages the surface 25 thereupon securing the slide 10 to the guide 11 by means of the said screw 14. In this position the axis or line of vision of the sighting member makes an angle o' with the vertical (see Fig. 1), " o' " representing the angle which the sighting member would have made with the vertical had the slide 10 been moved backwardly into engagement with the surface 25 after the preliminary observation of the target without having made any correction for the resistance of the wind to the movement of the falling object. With the sighting member 3 in the position stated in which the line of vision makes the angle o' with the vertical the aviator continues to approach the target, the operator continuing to sight through the tube 3 until the target comes in view and is located in the line of vision of the member 3. He then immediately releases the bombs which travel downwardly and forwardly on a curved trajectory E'A, (see Fig. 7) to the target.

The theory upon the apparatus operations will be clear by reference to a diagram shown in Fig. 7.

Let A represent the target.

Let AB represent the ground line.

Let CD represent the horizontal path of the aeroplane.

Let E represent the point at which the target would be released from the aeroplane to strike the target "A" if there were no horizontal resistance of the wind.

Let E' represent the point at which the bomb must be released from the aeroplane to strike the target "A" with the aeroplane traveling against the wind.

Let F represent the position in its path occupied by the aeroplane after it has traveled from the point "C" for a length of time equal to that required for an object to fall to the ground from a height indicated by the line "CD."

Let AD represent a vertical line through the point "A."

Let E'H' represent a vertical line through the point E'.

Let EH represent a vertical line through the point "E."

Let FG represent a vertical line through the point "F."

Let CB represent a vertical line through the point "C."

It must be proved that angle $o' = \text{angle } 70 \text{ DAE}'$.

If l =the distance along the axis of the screw 3 between the two sides (extended) of the angle o .

h =the distance between the pivotal axis of the sighting member and the axis of the screw.

c =the distance moved by the stop 24 and the slide 10 in making the correction for the resistance of the air to the movement of the dropped object.

d =the distance moved by the said stop and slide in sighting the target from point C to point F.

Then

$$\tan o' = \frac{d-c}{h} = \frac{d}{h} - \frac{c}{h} \quad (1)$$

But

d =the distance moved by the axis of pivot in sighting the target from point C to point F; so that

$$\tan p - \tan r = \frac{d}{h} \quad (2)$$

From (1) and (2)

$$\begin{aligned} \tan o' &= \tan p - \tan r - \frac{c}{h} \\ &= (\tan ACB - \tan AFG) - \frac{c}{h} \quad 100 \\ &= \frac{BG}{CB} - \frac{c}{h} \\ &= \frac{CF}{AD} - \frac{c}{h} \quad 105 \end{aligned}$$

Assuming the aeroplane to be traveling horizontally at a constant speed

$$CF = DE \quad (4)$$

From (3) and (4)

$$\tan o' = \frac{DE}{AD} - \frac{c}{h} \quad (5)$$

In preparing table 61 we use the relation

$$\frac{c}{h} = \frac{EE'}{AD} \quad (6)$$

From (5) and (6)

$$\tan o' = \frac{DE - EE'}{AD} \quad 120$$

$$= \frac{DE'}{AD}$$

$$= \tan DAE'$$

$$\text{or angle } o' = DAE'$$

which was to be proved. Whereby it appears that the sighting tube in its final position of

adjustment referred to is properly located to cause the target to appear in the line of vision through the sighting member at the moment at which the bomb must be released 5 from the aeroplane to fall upon the target.

The indicating means comprising the needle 60 and chart or scale 61 serve not only to make the desired correction for the resistance of the wind to the falling bomb or other object, but also to indicate the absolute speed 10 of the aeroplane with respect to the ground.

If s = speed of wind horizontally relatively to the ground.

s' = absolute speed of the aeroplane relatively to the ground.

v = the speed of the aeroplane relatively to the wind.

t = the time it takes for an object to fall distance DA.

20 Then

$$EE' = st \quad (7)$$

But

$s' = v - s$ (aeroplane going against wind)

25 and

$$s = v - s' \quad (8)$$

also

$$t = \sqrt{\frac{2AD}{g}} \quad (9)$$

From 7, 8 and 9

$$EE' = (v - s') \sqrt{\frac{2AD}{g}} \quad (10)$$

35

From (6)

$$EE' = \frac{c}{h}(AD) \quad (11)$$

40

From (10) and (11),

$$(v - s') = \left(\frac{c}{h}(AD) \right) \div \sqrt{\frac{2AD}{g}}$$

$$v - s' = \frac{c(AD)}{h} \div \sqrt{\frac{2AD}{g}}$$

50

$$s' = v - \frac{c(AD)}{h} \div \sqrt{\frac{2AD}{g}} \quad (12)$$

If s = the horizontal distance of pointer from the left hand end of scale—

55 Then

$$c = l - z$$

$$= h \tan DAE - z$$

60

$$= \frac{hDE}{AD} - z$$

$$= \frac{hs't}{AD} - z \quad (13)$$

From (12) and (13)

$$s' = v - \left[h \left(\sqrt{\frac{2AD}{g}} \right) \right] \left(\frac{hs't}{AD} - z \right)$$

70

$$= v - \frac{AD}{h \left(\sqrt{\frac{2AD}{g}} \right)} \left(\frac{hs'}{AD} \sqrt{\frac{2AD}{g}} - z \right)$$

75

$$= v - s' + \frac{z \sqrt{AD}}{h \sqrt{\frac{2}{g}}}$$

80

$$2s' = v + \frac{z \sqrt{AD}}{h \sqrt{\frac{2}{g}}} \quad (14)$$

and h are constant, and in the normal operation of an aeroplane v is constant, so that the only variables in (14) are s' , z and AD .

Accordingly if AD and z are known, s' is also known, and if s' and AD are assumed, z can be computed. From this relation lines each corresponding to a certain definite speed of the aeroplane with respect to the ground may be plotted in the scale as indicated. These lines in the chart shown are the curved lines extending upwardly and forwardly the numerals at the upper end of the chart indicating speeds in miles per hour for the various heavy lines adjacent to which said numerals are arranged. The vertical column of numerals, as already indicated, designate altitudes corresponding to the various adjacent horizontal lines. To determine the absolute speed of the aeroplane the operator is simply required to note the speed represented by the curved line which intersects the horizontal line corresponding to the altitude of the aeroplane at the point nearest the needle 60.

The light lines between the various heavy lines of the scale serve to indicate in connection with the heavy lines, as already pointed out, the correction in the position of the sighting member to be made for the horizontal resistance of the wind against the moving bomb or other falling object. The distance "c" between any heavy line and the corresponding light line to the left may be readily computed from equation (6) above where AD is known and EE' can be determined from equation 10 above.

Whereas I have shown and described the form of invention which I now consider best, numerous modifications may be made in the apparatus shown without departing from my invention.

What I claim and desire to protect by Letters Patent of the United States is:

1. In apparatus of the class described for use upon a body in motion, the combination of sighting means comprising a member pivoted for movement to change the

65

130

direction of the line of vision with respect to the vertical, and means co-acting with said member and operable to locate the same to cause the line of vision thereof to make with the vertical an angle, the tangent of which is equal to the quotient obtained when the distance traveled by the body in the time required by an object to fall from said body to the ground is divided by the 5 distance of the body from the ground, said apparatus having means for determining the correction of the angle of the line of vision to the vertical to provide for resistance of the wind to the falling object.

15. 2. In apparatus of the class described for use upon a body in motion, the combination of sighting means comprising a member pivoted for movement to change the direction of the line of vision with respect to the 20 vertical, and means co-acting with said member and operable to locate the same to cause the line of vision thereof to make with the vertical an angle, the tangent of which is equal to the quotient obtained when the 25 distance traveled by the body in the time required by an object to fall from said body to the ground is divided by the distance of the body from the ground, said apparatus having means for determining the correction 30 of the angle of the line of vision to the vertical to provide for resistance of the wind to the falling object, said last named means comprising a scale and co-acting pointer, one of which is movable with said sighting member.

35. 3. In apparatus of the class described, the combination of a movable sighting member and means for setting the same for determining when an object should be released 40 from a moving body to fall upon a target, said setting means comprising means for determining the correction of the setting of said sighting member to provide for the resistance of the wind to the falling object, said correction determining means indicating 45 the speed of the body relatively to the ground.

4. In apparatus of the class described, the combination of a sighting member and means 50 for setting the same to determine when an object should be released from a moving body to fall upon a target, said apparatus comprising means operable by the setting of said sighting member for indicating the speed of the body relatively to the ground.

5. In apparatus of the class described the combination of a movable sighting member, a stop therefor and unitary means for moving said sighting member in a given direction 60 and for moving said stop in the opposite direction.

6. In apparatus of the class described the combination of a movable sighting member, a stop therefor and unitary means for moving 65 said sighting member in a given direc-

tion and for moving said stop in the opposite direction, said sighting member being releasable from said means to permit movement thereof into operation relative to said stop.

70

7. In apparatus of the class described the combination of a movable sighting member, a stop therefor and unitary means for moving said sighting member in a given direction comprising a rotatable screw and for moving said stop in the opposite direction; said sighting member being releasable from said means to permit movement thereof into operation relative to said stop.

75

8. In apparatus of the class described, the combination of a pivoted sighting member, a stop therefor, a movable guide, a device connected with said sighting member and movable relatively to said guide, means for detachably securing said device to said guide, and means for moving said guide and said stop equal amounts.

85

9. In apparatus of the class described, the combination of a pivoted sighting member, a stop therefor, a movable guide, a device connected with said sighting member and movable relatively to said guide, means for detachably securing said device to said guide, and unitary means for moving said guide and said stop equal amounts in opposite directions.

90

10. In apparatus of the class described the combination of a pivoted sighting member, a rotatable screw having portions threaded in opposite directions, a non-rotatable stop 100 threaded upon one of said portions, a non-rotatable guide threaded on the other of said portions, a device connected with said sighting member and movable along said guide into engagement with said stop, and means for detachably securing said device to said guide.

105

11. In apparatus of the class described the combination of a movable sighting member, a stop therefor, means for moving said sighting member in a given direction comprising a rotatable screw and for moving said stop in the opposite direction; said sighting member being releasable from said means to permit movement thereof into operation relative to said stop, and means including speed increasing gearing for rotating said screw.

110

12. In apparatus of the class described, the combination of a movable sighting member, means co-acting with said member and operable to determine the position of said sighting member for sighting a target from a moving body adapted to travel at different heights and speeds at the moment when an object should be released from said body to fall upon said target, said means comprising a movable device adapted to be adjusted by preliminary observation of the target by said sighting member, and timing mechanism 125 130

having indicating means carried by said sighting member and visible when sighting with said sighting member.

13. In apparatus of the class described, 5 the combination of a movable sighting member, means co-acting with said member and operable to determine the position of said sighting member for sighting a target from a moving body adapted to travel at 10 different heights and speeds at the moment when an object should be released from said body to fall upon said target, said means comprising a movable device adapted to be adjusted by preliminary observation of the 15 target by said sighting member, and timing mechanism having an indicator arranged to move in the field of said sighting member, said sighting member having a reference mark for said indicator.
- 20 14. In apparatus of the class described the combination of a sighting member for sighting a distant object, and timing mechanism carried by said member and having an indicator arranged to move in the field of 25 said sighting member.

15. In apparatus of the class described the combination of a sighting member, timing mechanism having an indicator arranged to move in the field of said sighting member, 30 said sighting member having a reference mark for said indicator, and said timing mechanism being adjustable to set said indicator toward or away from said reference mark, and means for controlling the operation 35 of said timing mechanism.

16. In apparatus of the class described the combination of a movable sighting member, timing mechanism visible when sighting with said sighting member and means comprising a unitary operating member for 40 moving said sighting member and controlling the operation of said timing mechanism.

17. In apparatus of the class described, 45 the combination of a movable sighting member, means co-acting with said member, operable to determine the position of said sighting member for sighting a target from a moving body adapted to travel at different 50 heights and speeds at the moment when an object should be released from said body to fall upon said target, said means comprising a movable device adapted to be adjusted by preliminary observation of the 55 target by said sighting member, and means comprising a unitary operating member for

moving said sighting member and controlling the operation of said timing mechanism.

18. In apparatus of the class described, 60 the combination of a sighting tube for sighting a distant object and timing mechanism carried thereby and comprising indicating means visible without and within said tube.

19. In apparatus of the class described, 65 the combination of a sighting tube, timing mechanism carried thereby and comprising an indicator visible without and within said tube, and means for controlling the operation of said timing mechanism, said means 70 comprising a flexible member and means for shifting said flexible member longitudinally.

20. In apparatus of the class described, 75 the combination of a sighting member, timing mechanism carried thereby and comprising an indicator visible while sighting with said member, said timing mechanism being adjustable in position, and means for controlling the operation of said timing mechanism, said means comprising means movable with said timing mechanism during the adjustment thereof, and other means co-acting with said movable means in different positions of adjustment of said timing mechanism.

21. In apparatus of the class described for use on a moving body, the combination of movable sighting means comprising a device adapted for making a preliminary observation of the target, means for determining the location of the line of vision when an object is to be released from the body to fall on the target, and means whereby said last named means is set comprising a screw 90 for moving said device and location determining means equal distances.

22. In apparatus of the class described, 95 the combination of movable sighting means, means coacting with said sighting means and operable to determine the position of the line of vision for sighting a target from a moving body adapted to travel at different heights and speeds to determine when an object should be released from said body to fall upon said target, and timing mechanism having indicating means visible when sighting with said sighting means.

In testimony whereof, I have signed my name to this specification.

GEORGES ESTOPPEY.
